COMBINATION SMOKER'S APPLIANCE

Melvin J. Osborne, Lawn, Tex.

Application July 19, 1949, Serial No. 105,497

3 Claims. (Cl. 220—36)

1

This invention relates to smokers' equipment, and more particularly to a combination ash tray, cigarette lighter, and cigarette storage receptacle.

A main object of the invention is to provide a novel and improved combined cigarette lighter, ash tray, and storage receptacle of the electrically operated type, which is very simple in construction, very compact in size and which is neat in appearance.

A further object of the invention is to provide an improved combined ash tray, cigarette lighter and cigarette storage device, which is inexpensive to manufacture, which is very easy to operate, and wherein cigarettes may be stored without deterioration thereof, the ash tray portion of the device being very quiet in operation and being easy to empty whenever required.

Further objects and advantages of the invention will become apparent from the following description and claims and from the accompanying drawings, wherein:

Figure 1 is a top plan view of a combination smokers' device constructed in accordance with the present invention.

Figure 2 is a front end elevational view of the smokers' device of Figure 1.

Figure 3 is a rear end elevational view of the smokers' device of Figure 1.

Figure 4 is a vertical longitudinal cross sectional view taken on line 4—4 of Figure 1.

Figure 5 is a fragmentary enlarged detail view of the damping cylinder employed with the movable elements of the ash tray portion of the device of Figure 1.

Figure 6 is a cross sectional view taken through the damping cylinder of Figure 5.

Figure 7 is a cross sectional detail view taken on line 7—7 of Figure 6.

Figure 8 is a cross sectional detail view taken through the plunger of the damping device of Figure 5, said view being taken on line 8—8 of Figure 6.

Figure 9 is a cross sectional view taken on line 9—9 of Figure 8.

Referring to the drawings, 11 designates the housing of the device, said housing being made of sheet metal, plastic or the like, and being mounted on a base 12 of felt or other suitable cushioning material to protect the underlying surface of the table or other article of furniture on which the device is to be placed. As shown in Figure 4, the housing 11 may be generally rectangular in shape and has an inclined upper front wall portion 13. Mounted in wall portion 13

13 is a conventional low-voltage electrical cigarette lighter of the "pop-up" type, shown at 14. Mounted in said wall portion 13 adjacent lighter 14 is a push-button switch 15. Designated at 16 is a drawer slidably mounted in a rectangular aperture formed in the lower portion of the front wall of housing 11, said drawer carrying an upwardly projecting abutment spring 17 at its rear wall adapted to engage the inner surface of the front wall of the housing 11 to limit outward movement of the drawer 16 and to prevent said drawer from being completely withdrawn from the housing. Drawer 16 is provided with a handle or knob 18 for manipulating same. Said drawer is employed as a receptacle for cigarettes, cigars, or the like. A partition 19 is provided in the housing 11 around drawer 16 to shield the drawer from heat from other parts of the device, thereby preventing excessive drying of the contents of the drawer.

The top wall of housing 11, shown at 20, is formed at its rear portion with a downwardly flanged opening 21, the flange of the opening being tapered downwardly and inwardly as shown at 22. Secured on top wall 20 around the margin of the opening are a plurality of cigarette or cigar holders 23. Pivoted in the housing on a transverse bolt 24 secured therein is an arcuate lever 25 formed with a straight lower arm 26. Connected between the end of arm 26 and the bottom wall of the housing is a coiled spring 27 biasing lever 25 counterclockwise, as viewed in Figure 4. Secured to the upper end of arm 25 is a downwardly concave cup or plate member 28 which normally abuts the bottom rim of flange 22 due to the biasing effect of spring 27.

Designated at 29 is a large rectangular receptacle slidably mounted on opposing angle bars 30 secured to the side walls of housing 11 and being movable rearwardly out of the housing through a rectangular aperture formed in the rear wall of said housing. The rear wall of receptacle 29, shown at 31, is normally received in a marginal recess formed around said rectangular aperture, whereby it is substantially flush with the housing rear wall. The receptacle rear wall 31 is formed with an inwardly pressed recess 32 defining a hand hold for withdrawing the receptacle from the housing 11 whenever desired. The receptacle 29 is normally positioned beneath the flanged opening 21 to receive cigarette butts, ashes, and the like, when opening 21 is uncovered by the rotation of lever 25 clockwise, as viewed in Figure 4, and the consequent downward movement of plate member 28. Secured

to the front wall of receptacle 29 is the upwardly and inwardly extending bracket 33 carrying an abutment member 34 at its top end. When plate member 28 is swung downwardly to open position, said plate member strikes the abutment 34 causing ashes or other material on the plate member to be shaken loose therefrom and to drop into the receptacle 29.

Pivoted at 35 to the top wall of housing 11 forwardly of opening 21 is a solenoid unit 36 having a plunger 37 which is pivotally connected to arm 26 at 38. When solenoid unit 36 becomes energized, plunger 37 is drawn upwardly into the solenoid, causing lever 25 to be rotated clockwise, as viewed in Figure 4. Pivoted to the top wall of housing 11 at 39, forwardly adjacent opening 21 is a cylinder 40 having an open bottom end. Slidably positioned in cylinder 40 is a piston 41 carried on a rod 42 which is pivotally connected to the upper portion of lever 25, at 43. Cylinder 40 is formed at its upper portion with a small aperture 44. Piston 41 is formed with a plurality of apertures 45 normally covered by a flexible disc 46, of rubber or the like, secured to the top surface of the piston. When lever 25 is moved clockwise by the energization of solenoid 36, the piston 41 is drawn downwardly in cylinder 40, the rubber flap member 46 allowing air to move through the apertures 45 into the upper portion of the cylinder, whereby the piston and cylinder provide very little resistance to the clockwise rotation of lever 25. Plate member 28 therefore moves downwardly relatively rapidly to uncover opening 21. As soon as solenoid 36 becomes de-energized, spring 27 returns lever 25 to its normal position, shown in Figure 4, wherein plate member 28 covers opening 21. The return movement of lever 25 is retarded, however, by the resistance offered by cylinder 40 to the upward movement therein of piston 41, since under these conditions the flap member 46 seals the openings 45 and the air trapped in the cylinder can only escape through the small opening 44. This introduces a substantial time delay in the return of plate member 28 to normal closed position. Sufficient time is therefore provided for ashes, cigarette butts, and the like, to slide over plate member 28 into the receptacle 29.

Designated at 47 is the line cord which enters the rear wall of housing 11 through a grommet 48. Line cord 47 is connected to the primary of a step-down transformer 49 secured to the bottom wall of housing 11. The secondary of transformer 49 is connected by suitable wires 50 and 51 to the terminals of the lighter 14. One terminal of solenoid 36 is connected by a wire 52 to wire 51. The other terminal of said solenoid is connected by a wire 53 to one terminal of switch 15. The remaining terminal of switch 15 is connected by a wire 54 to wire 50. When switch 15 is closed, the solenoid 36 becomes energized from the secondary of transformer 49 by a circuit comprising wire 50, wire 54, switch 15, wire 53, solenoid 36, wire 52, and wire 51. The energization of solenoid 36 causes the plate member

28 to be swung downwardly to open position, as above described.

While a specific embodiment of a combination smoker's device has been disclosed in the foregoing description, it will be understood that various modifications within the spirit of the invention may occur to those skilled in the art. Therefore, it is intended that no limitations be placed on the invention except as defined by the scope of the appended claims.

What I claim is:

1. A smoker's device of the character described comprising a housing formed in its top wall with an opening to receive cigarette ashes and the like, a closure plate in said housing and pivoted thereto, said plate being arranged to close off said opening, spring means biasing the plate to closing position, electro-magnetic means connected to said plate and arranged to swing the plate downwardly responsive to energization thereof, and retarding means connected between the plate and the housing, slowing down the movement of the plate.

2. A smoker's device of the character described comprising a housing formed in its top wall with an opening to receive cigarette ashes and the like, a closure plate in said housing and pivoted thereto, said plate being arranged to close off said opening, spring means biasing the plate to closing position, electro-magnetic means connected to said plate and arranged to swing the plate downwardly responsive to energization thereof, a damping cylinder pivotally connected to the housing, a piston in said cylinder, and means connecting said piston to the closure plate, and check valve means on the piston limiting free movement of the piston in the cylinder.

3. A smoker's device of the character described comprising a housing formed in its top wall with a downwardly flanged opening to receive cigarette ashes and the like, a closure plate in said housing and pivoted thereto for swinging movement around a horizontal axis, said plate being arranged to close off said opening, spring means biasing the plate to closing position, electro-magnetic means connected to said plate and arranged to swing the plate downwardly responsive to energization thereof, switch means carried on the housing, circuit means including said switch means connected to said electro-magnetic means, a damping cylinder pivoted to the housing, said cylinder having a small opening formed therein adjacent its pivoted end and being open at its other end, a piston in said cylinder, means connecting said piston to the closure plate, said piston being formed with an opening, and a resilient flap member secured to said piston and overlying said opening, said flap member being yieldable in response to outward movement of the piston with respect to said pivoted end, whereby the closure plate is unretarded in its opening movement but is retarded in its closing movement.

MELVIN J. OSBORNE.
